CLAIM

The ornamental design for a plunger and finger grip for a syringe, as shown and described.

DESCRIPTION

FIG. 1 is a perspective view of the plunger and finger grip viewed from the front and right;

FIG. 2 is a front elevation view thereof;

FIG. 3 is a rear elevation view thereof;

FIG. 4 is a left side elevation view thereof;

FIG. 5 is a right side elevation view thereof;

FIG. 6 is top plan view thereof; and,

FIG. 7 is a bottom plan view thereof.

The broken line showing is for the purpose of illustrating portions of the article and forms no part of the claimed design. The broken line which defines the bounds of the claimed invention forms no part of the claimed design.
